Primary Examiner — Catherine S Posthauer(74) *Attorney, Agent, or Firm* — Tuggle Duggins P.A.;
Blake P. Hurt(57) **CLAIM**

The ornamental design for a transport tray, as shown and described.

DESCRIPTION

FIG. 1 is a top, front, right side perspective view of a transport tray showing my new design;
 FIG. 2 is a top plan view thereof;
 FIG. 3 is a left side elevational view thereof, the right side elevational view being a mirror image thereof;
 FIG. 4 is a rear elevational view thereof, the front elevational view being a mirror image thereof; and,
 FIG. 5 is a bottom plan view thereof.

1 Claim, 5 Drawing Sheets(56)
